UNITED STATES PATENT OFFICE.

ROY S. NELSON AND WINFIELD S. NELSON, OF OKLAHOMA, OKLAHOMA, ASSIGNEES OF ONE-THIRD TO C. H. FLEET, OF OKLAHOMA, OKLAHOMA.

OIL-BURNER.

1,193,413.

Specification of Letters Patent.

Patented Aug. 1, 1916.

Application filed October 9, 1915. Serial No. 55,007.

To all whom it may concern:

Be it known that we, ROY S. NELSON and WINFIELD S. NELSON, citizens of the United States, residing at Oklahoma, in the county 5 of Oklahoma and State of Oklahoma, have invented certain new and useful Improvements in Oil-Burners; and we do hereby declare the following to be a full, clear, and exact description of the invention, such as 10 will enable others skilled in the art to which it appertains to make and use the same.

The invention relates to improvements in oil burners.

The object of the present invention is to 15 improve the construction of oil burners and to provide a simple, practical and comparatively inexpensive oil burner designed for use in stoves, furnaces and various other heating devices and adapted for burning 20 coal oil and other hydrocarbon.

With these and other objects in view the invention consists in the construction and 25 novel combination and arrangement of parts hereinafter fully described, illustrated 30 in the accompanying drawings and pointed out in the claims hereto appended, it being understood that various changes in the form, proportion and minor details of construction may be resorted to without departing 35 from the spirit or sacrificing any of the advantages of the invention.

In the drawings Figure 1 is a side elevation of an oil burner constructed in accordance with this invention, Fig. 2 is a central vertical sectional view of the same, Fig. 3 is a similar view taken at right angles to Fig. 2, Fig. 4 is a horizontal sectional view on the line 4—4 of Fig. 3, Fig. 5 is a side elevation of the upper section of the burner 40 proper. Fig. 6 is a reverse plan view of the base, Fig. 7 is a detail view of the retort.

Like numerals of reference designate corresponding parts in the several figures of the drawings.

45 In the accompanying drawings in which is illustrated the preferred embodiment of the invention, the oil burner comprises in its construction, a retort and a burner proper having a base 1 of substantially cylindrical form provided at the bottom with supporting legs or lugs 2 and having an in- 50 wardly extending horizontal annular flange 3 also located at the bottom of the base and forming a seat for the lower end of a co-acting inner or upper section 4 composed of 55 upper and lower portions 5 and 6, the lower portion 6 being tapered downwardly and having an imperforate bottom 7.

The upper portion 5 is of greater diameter than the lower portion 6 and the upper section is provided at the juncture of the two portions with a shoulder 8 adapted to rest upon the upper edge of the base. The upper section of the burner proper is also provided below the horizontal shoulder 65 8 with an annular face 9 arranged vertically and fitting the interior of the base at the top thereof as clearly shown in Fig. 2 of the drawings. By this construction a tight connection is made between the upper section and the base at the top and bottom of the latter. The upper section is also provided at the bottom of its lower or inner portion with an exterior annular recess 10 which forms a shoulder and which fits with- 75 in the annular flange 3 of the base. The annular flange 3 extends from the vertical walls of the base to the bottom of the upper section and the tapering of the latter forms an intervening space 11 between it 80 and the base. The flange 3 is provided with air inlet openings 12 which are located at the bottom of the intervening annular space 11 and the lower tapered portion of the inner section is provided with inclined perforations 13 arranged at intervals and adapted to permit the air to pass from the intervening space to the interior of the upper section.

85 The upper cylindrical portion of the upper section is located in substantially the vertical plane of the walls of the base and it is provided at opposite sides with recesses 14 in which are arranged the terminal portions 15 and 16 of a transversely disposed 95 pipe 17 which has a depressed intermediate portion formed by downwardly extending bends 18. The end 15 of the transverse pipe 17 has an imperforate end wall or closure 19 of any desired construction. The other end 100 16 is connected by a vertical pipe or branch portion 20 with a top transversely disposed

generating pipe 21 located above and in spaced relation with the lower transverse pipe 17 connected with the vertical portion 22 of the supply pipe. The lower transverse pipe is preferably rectangular or oblong in cross section while the top transverse pipe is preferably circular in cross section and the latter is equipped with a retort 23 which is located directly above a nipple 24 extending upwardly from the center of the depressed portion of the lower transverse pipe 17.

The retort is preferably in the form of a cylindrical casing provided at opposite sides with openings 25 to receive the top transverse pipe 21 which is composed of two sections spaced apart to receive the casing between them. The cylindrical casing which has a top plate 23^a is provided with a series of spaced baffle plates 26 adapted to cause the liquid or gaseous fuel to travel back and forth across the cylindrical casing of the retort before passing to the nipple 24. The top plate 23^a is secured by screws or other suitable fastening devices to the body portion of the cylindrical casing. The lower portion of the upper section of the burner proper constitutes a starting cup and a quantity of liquid hydrocarbon is placed in the lower imperforate portion of the upper section and is ignited causing the flame to impinge against the bottom pipe and also the top transverse pipe and heating the top and bottom pipes sufficiently to generate gas from oil fed to the pipes. The oil in passing through the upper generating pipe is converted into a gas and the gas passes downwardly through the connecting pipe 20 and is discharged through the nipple 40 where it burns beneath the retort.

The oil burners may be constructed of any suitable material and of any desired size to adapt them for the particular heating apparatus in which they are to be used and it will be clear that owing to the relatively small bore of the nipple that the gas generated in the pipes will be discharged under pressure and a constant supply of gas maintained. The lugs or legs 2 support the air inlet openings 12 above the grate or other supporting surface upon which the oil burner is placed and a proper supply of air to the interior or chamber of the inner casing or section 4 is maintained both in the initial starting of the heater and in the operation of the same after the generation of gas in the pipe is complete. While it is preferable to use coal oil as a fuel a heavier oil may of course be employed.

60 What we claim is:—

1. A burner of the class described including a burner proper composed of a base, and an upper section extending into the base and fitting against the same at the top and

bottom thereof and spaced therefrom between the top and bottom of the said base to form an intervening space, said base being provided at the bottom of the intervening space with an air inlet and the said upper section having an air outlet communicating with the said base, said upper section being closed at the bottom to form a starting cup, and a pipe extending across the upper section and provided at an intermediate point with a discharge aperture. 75

2. An oil burner of the class described including a substantially cylindrical base provided at the bottom with an inwardly extending flange having apertures and an upper section of substantially cylindrical form fitting within the base and the flange and forming an intervening air space, said upper section being closed at the bottom to form a starting cup and provided with perforations located at the upper portion of the said intervening space, and a transverse pipe supported by the upper section and provided with a discharge nipple. 85

3. An oil burner of the class described including a burner proper comprising a base 90 consisting of a casing and provided at the bottom with an inwardly extending flange having an air inlet, an upper section consisting of an upper portion and a lower reduced portion fitting within the outer section or 95 base and forming an intervening air space, said lower portion being also provided with an air passage communicating with the said intervening space, and a pipe extending across the upper section and provided with 100 an aperture for the escape of gas.

4. An oil burner of the class described including a burner proper comprising a base of substantially cylindrical form provided at the bottom with an inwardly extending 105 flange having an air inlet, an upper section consisting of an upper substantially cylindrical portion and a lower reduced portion fitting the base and the flange thereof and forming an intervening air space and having a closed bottom to form a starting cup, said upper section being also provided with apertures communicating with the said intervening space, a lower transverse pipe extending across the upper portion of the 115 upper section and having an aperture for the discharge of gas, a top generating pipe located above the lower transverse pipe, and means for connecting the said pipes. 110

5. An oil burner of the class described 120 including a burner proper comprising a base and an upper section supported by the base at the top and bottom thereof and spaced therefrom between the top and bottom of the base to form an intervening 125 air space, said base and upper section having inlet and outlet apertures communicating with the said air space and the upper

section being closed at the bottom to form a starting cup, a lower transverse pipe extending across and supported by the upper section at opposite sides thereof and provided at an intermediate point with a discharge aperture, and an upper generating pipe located above the discharge aperture.

In testimony whereof we affix our signatures in presence of two witnesses.
